UNITED STATES PATENT OFFICE.

HARVEY C. MUMMERT, OF FLORAL PARK, NEW YORK.

BUTTON.

1,306,922.

Specification of Letters Patent. Patented June 17, 1919.

Application filed March 29, 1919. Serial No. 285,959.

To all whom it may concern:

Be it known that I, HARVEY C. MUMMERT, a citizen of the United States, residing at Floral Park, in the county of Nassau and State of New York, have invented certain new and useful Improvements in Buttons, of which the following is a specification.

My invention relates to buttons and has reference more particularly to buttons for wearing apparel.

As at present made buttons for wearing apparel either break or pull off. This is particularly true if the garments upon which the buttons are used are washed or 15 laundried by machine. Ironing machines break the buttons and washing machines, such as wringers, pull them off. In ironing, the contact between the iron and the button is sufficient to break the button and in drying, the entry of the button between the rolls of a clothes wringer is sufficient to either tear the garment or pull the button off. Metal buttons, glass buttons, bone buttons, composition buttons and in fact all 25 character of buttons have been proposed. In no instance, however, has a material or combination of material been proposed which would overcome the objectionable features above pointed out.

It is realized that rubber alone and rubber and metal in combination have been used in the manufacture of buttons. Buttons thus characterized are not used nor intended to be used in connection with wash 35 garments and more particularly the garments of children. Rubber buttons it is true can be used with good results in connection with metal bound or rigid button holes. They cannot however be used with good results in connection with the ordinary button hole. In the first place rubber alone is entirely too elastic to hold in button holes of the non-rigid type and too soft to admit of its attachment to a garment by sewing. Combined metal and rubber buttons although strong, lack flexibility and are intended to be used primarily in connection 45 with garter clasps and the like.

The button of the present invention is distinguished from the buttons above mentioned by its inherent resiliency and strength. A combination of rubber and fabric is used. Both such materials are inherently flexible and in combination provide a button especially adapted to garment use wherein non-rigid button holes are provided. The fabric is embedded in the rub-

ber and the button apertured to receive the fastening means. If desired, the button head in the vicinity of the apertures may be 50 enlarged to provide a shank. A button thus formed can be fastened to a garment in the usual manner by sewing (the fabric being relied upon to hold the thread) or the reinforcing fabric may be extended without the 55 confines of the rubber to provide for its fastening. Inherent resiliency, flexibility and strength rather than elasticity are the distinguishing features of the button herein proposed.

In the drawings wherein like characters of reference designate like or corresponding parts:

Figure 1 is a plan view of the button; 75
Fig. 2 is an edge view;
Fig. 3 is an enlarged cross sectional view;
Fig. 4 is a similar view, the parts comprising the button being detached;

Fig. 5 is an enlarged cross sectional view of a modification, and

Fig. 6 is an inverted plan view of the button illustrated in Fig. 5.

In the embodiment of the invention selected for illustration, rubber and fabric are used in combination in the formation of the 85 button head which is designated as 10. The shank, designated as 11, although shown integrally formed upon the underneath face of the head 10, may be attached to it by any suitable means. Rubber is used in the formation of the head portion because of its inherent flexibility and resiliency, the flexibility being relied upon to admit of its distortion and the resiliency relied upon to insure the return of the head to its original 95 position or form. It is not intended that the head 10 should be stretched or compressed to pass through the button hole. For ordinary use the button possesses sufficient rigidity to button and unbutton in the 100 usual manner. It is however sufficiently pliable and resilient to pass through the button hole without injury to either should the button or the garment in which the button hole is formed be suddenly pulled or jerked.

Within the button head thread holes 12 are formed, or if desired, the button may be sewed on by machine and the threads carried through the button without first forming the thread holes 12. For ordinary use, 110 however, it is preferred that thread holes be provided.

Rubber in and of itself lacks sufficient strength or toughness to prevent the threads

from pulling through. The threads, due to their fineness, bite into and cut the rubber. This is especially true after the use of the button for a short period of time. For this reason a reinforcing strip 13 (fabric preferred) is either fastened to or embedded in the button head in the vicinity of the thread holes 12 since it is at this point or rather these points that reinforcement is most needed. It will be noted (see Figs. 1 to 4 inclusive) that the thread holes 12 pass through both the rubber and the fabric and that the latter when embedded in the head portion 10 is removed from view. It is not essential however, that the reinforcing fabric 13 be thus embedded since it is entirely practical to fasten it upon either outside face of the head. What is most important is that the attaching means is carried through or at least to the fabric, as in this manner only can the required strength be obtained.

In embedding the fabric in the button head it (the fabric strip 13) is laid between two layers of rubber of a size preferably somewhat larger than the fabric strip. The edges of the layers of rubber thus overhang or extend beyond the fabric upon all sides. The layers of rubber (see Fig. 4) are designated as 14 and 15 respectively. Between the layer of rubber 15 and the fabric 13 a wad of rubber 16, upon the sealing of the layers of rubber together, distends the layer 15 and in the finished button provides what I have hereinbefore designated the shank.

The sealing of the layers of rubber together is accomplished by vulcanization. In vulcanizing the rubber or layers 14 and 15 and the wad 16 are heated in the usual manner until the melted rubber or molecules thereof enter the pores of the fabric strip 13. This having been done the rubber is allowed to cool, congeal and dry. By extending the edges of the layers of rubber 14 and 15 beyond the fabric strip 13 the layers of rubber during the vulcanizing process are brought together to provide at the edge of the button an even strong seal. The thread holes are formed in the button after it is made.

In the modification illustrated in Figs. 5 and 6 the reinforcing strip is embedded in the head although for a portion of its length extended without the confines of the rubber. The head portion of the modified button is designated as 18 and its reinforcing fabric as 19. The latter, as indicated, comprises separate strips, each of which is extended centrally without the head to provide tabs 20 for the attachment of the button by sewing the tabs to the garment, rather than by carrying the threads through apertures formed in the button head.

A button characterized as herein disclosed, is especially suited to garment use and more especially to use in connection with the garments of children. When thus used there is but slight possibility of the buttons pulling off or breaking due to the resiliency of the button. The button is buttoned or unbuttoned in the usual manner, *i. e.*, by distorting the button hole to allow the button to pass through it. It is however, sufficiently pliable and resilient to be itself distorted without tearing the garment or enlarging the button hole should occasion arise necessitating its passage through the button hole without intentionally distorting it. It is this characteristic, together with the characteristic of strength, which I desire to emphasize.

In manufacture the buttons may be made individually or in series. If made in series the individual buttons can be stamped or punched.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What is claimed is:

1. A button comprising a resilient head portion having means attached to it to reinforce it without impairing its resiliency.

2. A button comprising a resilient head portion having a means embedded therein to reinforce it without impairing its resiliency.

3. A button comprising a resilient head portion having apertures formed therein together with means attached to the button head to reinforce it in the vicinity of said apertures.

4. A button comprising a resilient head portion having apertures formed therein together with a fabric strip cemented to the button head to reinforce it without impairing its resiliency, the apertures formed in the head being extended through the fabric.

5. A flexible button comprising a strip of fabric and a plurality of layers of resilient material, the strip of fabric being disposed between and being somewhat smaller than the layers of resilient material whereby the overhanging edges of the latter may be vulcanized.

In testimony whereof I hereunto affix my signature in the presence of two witnesses.

HARVEY C. MUMMERT.
